UNITED STATES PATENT OFFICE.

NERO OSTENBERG AND PONTUS OSTENBERG, OF SAN JOSE, CALIFORNIA.

INTENSIFIER FOR MAGNETOS.

1,246,312.

Specification of Letters Patent. Patented Nov. 13, 1917.

Application filed March 22, 1917. Serial No. 156,699.

To all whom it may concern:

Be it known that we, NERO OSTENBERG and PONTUS OSTENBERG, residents, respectively, of San Jose, in the county of Santa Clara 5 and State of California, have invented certain new and useful Improvements in Intensifiers for Magnetos, of which the following is a specification.

Our invention relates to spark intensifiers 10 for magnetos, in which the intensifying or interrupting detents or pawls are thrown into or out of action automatically according to the speed of the armature and driving shafts in connection with which it is used.

One object of the present invention is to 15 produce an intensifier for magnetos which will successfully cause a succession of hot sparks or kick-off sparks in the engine cylinders when the engine is started, but which 20 will automatically become inoperative when the engine is fairly started, again automatically assuming an operative position as the engine slows down to a stop.

Another object is to produce an intensifier 25 operated by the centrifugal force manifested by the revolving shafts and parts connected thereto, thereby simplifying the construction of the device and rendering it economical to manufacture, easy of installation, and 30 greatly reducing the number of wearing parts and consequently rendering the device more durable than those forms commonly used.

With these and other objects in view our 35 invention consists in the new and novel construction, provision, formation, combination and relative arrangement of parts, members and features, all as hereinafter described, shown in the drawings, and finally pointed 40 out in the claims.

In the drawings:

Figure 1 is a vertical transverse section through our improved intensifying device operatively connected to the armature shaft 45 of a magneto and a driving shaft.

Fig. 2 is a sectional view on line A—A of Fig. 1.

Fig. 3 illustrates a modified form of detent mechanism.

50 Fig. 4 illustrates a second modified form of detent mechanism.

Fig. 5 is a plan view of the detent shown in Fig. 4.

Similar characters of reference refer to 55 similar parts throughout the several views.

At 1 is shown a portion of a magneto

mounted on plate 2 and provided with armature shaft 3, armature shaft 3 being alined with driving shaft 4 mounted in bearings 5. At 6 is shown a circular plate secured to driving shaft 4, and at 7 is a second plate secured to armature shaft 3, plate 7 preferably being provided with a flange 8 adapted to loosely inclose plate 6 and thereby form an inclosed chamber to contain the working parts of the mechanism. Plates 6 and 7 are connected by a spring 9 which encircles shafts 3 and 4 the ends thereof being set in plates 6 and 7 as shown at 10 and 11 respectively. 70

At 12 is shown a stop rigidly fixed in plate 2 and projecting outwardly until nearly touching flange 8 on plate 7. Rigidly mounted on the under side of plate 7 near the perimeter thereof and vertical thereto is pin 75 13 having a detent 14 pivotally mounted thereon. Detent 14 is so formed as to have one short arm 15 projecting outwardly through opening 16 formed in flange 8 and having a flat end surface 17 adapted to engage stop 12, and a longer heavier arm 18 projecting backwardly within flange 8 and having a tripping-pin engaging surface 19. Detent 14 is so formed as to have a limited swinging movement on its pivotal pin 13. 80 At 20 is shown a tripping pin rigidly set in plate 6, normally placed a distance from the surface 19 on arm 18, but capable of contacting with said surface 19 when the device is operating as hereinafter described. A 85 90 spring 21 is secured to flange 8 and operates against the outer edge of detent 14.

In the illustration we have shown a second detent and tripping pin mounted in the same manner as above described and designated by similar numerals accompanied by an appropriate letter, this second detent mechanism being positioned diametrically opposite the first and thereby providing a double intensifying device for use with a 100 two cylinder engine. While this device is shown as adapted for use with a two cylinder engine it is evident that it may be readily adapted for use with engines of one, two, three or more cylinders. 105

In operation, when the engine is turned over slowly, armature shaft 3 is of course revolved by shaft 4 through the medium of spring 9 and plates 6 and 7 to which the spring is secured. Detent 14 being in a normal position as shown in solid lines it is carried around with plate 7 until surface 17

comes in contact with stop 12 whereupon the movement of detent 14, plate 7 and armature shaft 3 is stopped until tripping-pin 20 strikes surface 19 of arm 18 and forces arm 18 outwardly and arm 15 inwardly so that detent 14 assumes the position shown in dotted lines at 22, whereupon spring 9, being released, suddenly throws armature shaft 3 and the parts connected thereto forward a distance until stopped by pin 20^a, thereby operating magneto in such a manner as to produce a hot spark as desired. This movement of course removes pin 20 from surface 19 so that the spring 21 again throws arm 18 inward and arm 15 outward thereby setting detent 14 in position to contact with stop 12 during the next revolution. When the engine has gained sufficient speed this device is automatically rendered inoperative because the centrifugal force operates to throw the longer and heavier arm 18 of detent 14 outwardly, overcoming the very light pressure of spring 21, and thereby throwing short arm 15 inwardly and out of an operative position, said spring 21 automatically setting the detent 14 into an operative position when the engine slows down to a stop and the centrifugal force acting upon it becomes negligible. It is clear, of course, that while spring 21 is considered necessary when the device is operating in a vertical position as shown in Fig. 1 it is not an essential element when the device is operating in a horizontal position as shown in Fig. 2 with stop 12 positioned substantially as shown with relation to members 6 and 7. In the latter case arm 15 is automatically thrown outward by the force of gravity operating upon arm 18 when said arm 15 approaches stop 12 until the member 7 has gained sufficient speed to overcome the force of gravity and maintain said arm 15 in the position indicated in dotted lines at 22.

Another embodiment of our invention is shown in Fig. 3 in which shafts 3 and 4 revolve in an opposite direction to that indicated in Fig. 2, and detent 14 is formed with an engaging surface 23 to engage a stop 12. In this instance detent 14 is held in the operative position by spring 24 secured to arm 18 of detent 14 and a pin 24^a set in plate 6, and is tripped by a pin 24^b set in plate 6 and operating against the inner edge of detent 14 when moved forward by revolving plate 6. When detent 14 is thrown out of operation as described and jumps forward with the parts on which it is mounted by the released tension on spring 9, its forward movement is arrested by pin 24^c set in plate 7. When the engine has gained sufficient speed the detent 14 is held in an inoperative position by centrifugal force acting upon arm 18 and thereby holding it in an extended position, spring 24

again moving it to an operative position when the speed of the revolving parts is sufficiently diminished.

In the embodiment shown in Fig. 4, stop 12 is formed with a short terminal arm 12^a. Detent 14 is formed as a bar having an arm 14^a projecting from its outer end and adapted to engage the arm 12^a of stop 12 when drawn inwardly. Detent 14 slides in guide 25 secured to plate 7 and is normally held in an operative position by spring 26 attached thereto and to pin 27 set in plate 7. The rapid revolution of plate 7 causes detent 14 to overcome the light tension of spring 26 and move outwardly into an inoperative position in which it is shown, the dotted lines 28 indicating the operative position. Detent 14 is tripped by pin 29 set in plate 6 and operating against beveled edge 30 of detent 14. The forward movement of plate 7 is arrested by guide 25 coming in contact with a pin 31 set in plate 6.

It is understood of course that while we have herein shown and described certain embodiments of our invention, that changes in form, construction and operation may be made within the scope of the appended claims, the embodiments disclosed serving to make clear the essential elements of our invention.

Having thus described our invention, what we claim as new and desire to secure by Letters Patent, is:—

1. The combination with a driven member mounted on the armature shaft of a magneto and a driving member yieldingly connected thereto, of a stop positioned adjacent said members, and one or more detents pivotally and eccentrically mounted on said first mentioned member normally positioned to engage said stop when said members are slowly revolved and centrifugally actuated to an inoperative position when said members are rotated at high speed. 100

2. The combination with a driven member mounted on the armature shaft of a magneto and a driving member yieldingly connected thereto, of a stop positioned adjacent said members, and one or more detents pivotally and eccentrically mounted on said first mentioned member normally positioned to engage said stop when said members are slowly revolved, and means carried by said second mentioned member for automatically removing said detent or detents from an operative to an inoperative position at predetermined intervals, said detent or detents being centrifugally actuated to maintain an inoperative position when said members are revolving at high speed. 115

3. The combination with a driven member mounted on the armature shaft of a magneto and a driving member yieldingly connected thereto, of a stop positioned ad- 120

- jacent said members, one or more detents pivotally and eccentrically mounted on said first mentioned member and adapted to engage said stop, means for automatically positioning said detent or detents in engagement with said stop when said members are slowly revolved, means carried by said second mentioned member for disengaging said detent or detents from said stop at predetermined intervals, and means for automatically maintaining said detent or detents in an inoperative position with relation to said stop when said rotating members are revolving at high speed.
5. The combination with a driven member mounted on the armature shaft of a magneto and a driving member yieldingly connected thereto, of a stop positioned adjacent said members, and one or more detents pivotally mounted on said first mentioned member, each detent having a short arm travelling in the path in which said stop lies and making contact with said stop when said members are slowly revolved and a heavier arm yieldingly connected to said first mentioned member, means for breaking the contact of said short arm and said stop at a predetermined interval, said heavier arm being centrifugally operated to maintain 30 said short arm in an inoperative position when said members have attained a higher speed.
6. The combination with a driven member mounted on the armature shaft of a magneto and a driving member yieldingly connected thereto, of a stop positioned adjacent said members, one or more detents pivotally and eccentrically mounted on said first mentioned member and adapted to engage 35 said stop, means for automatically positioning said detent or detents in engagement with said stop when said members are slowly revolved, means carried by said second mentioned member for disengaging said detent or detents from said stop at predetermined intervals, and centrifugally operated means for automatically maintaining said detent or detents in an inoperative position with relation to said stop when said members are revolving at high speed.
7. The combination with a driven member mounted on the armature shaft of a magneto and a driving member yieldingly connected thereto, of one or more detents pivotally and eccentrically mounted on said first mentioned member, a stop mounted to engage said detent or detents and lock said first mentioned member against movement when said second mentioned member is slowly revolved, means mounted on said second mentioned member for disengaging said detent or detents from said stop at predetermined intervals, means mounted on said second mentioned member for limiting the forward movement of said first mentioned member with relation to said second mentioned member when said detent or detents are disengaged from said stop, and centrifugally operated means for maintaining said detent or detents in an inoperative position with relation to said stop when said members are rotated at high speed.
8. The combination with a driven member mounted on the armature shaft of a magneto and a driving member yieldingly connected thereto, of one or more detents pivotally and eccentrically mounted on said first mentioned member, a stop mounted to engage said detent or detents and lock said first mentioned member against movement when said second mentioned member is slowly revolved, means mounted on said second mentioned member for disengaging said detent or detents from said stop at predetermined intervals, means mounted on said second mentioned member for limiting the forward movement of said first mentioned member with relation to said second mentioned member when said detent or detents are disengaged from said stop, centrifugally operated means for maintaining said detent or detents in an inoperative position with relation to said stop when said members are rotated at high speed, and means for automatically returning said detent or detents to engagement with said stop as said members cease rotating.
- In testimony whereof we have hereunto affixed our signatures this 15th day of March, 1917.
